UNITED STATES PATENT OFFICE.

CHARLES E. MACFARLANE, OF SEATTLE, WASHINGTON.

SKYLINE LOGGING SYSTEM.

Application filed March 1, 1923. Serial No. 622,006.

To all whom it may concern:

Be it known that I, CHARLES E. MACFARLANE, a citizen of the United States of America, and resident of the city of Seattle, in the county of King and State of Washington, have invented certain new and useful Improvements in Skyline Logging Systems, of which the following is a specification.

My invention relates to logging systems, and particularly to the type which employs sky lines or elevated cables along which a log-supporting carriage is hauled. My invention is equally applicable to the fixed or the slack sky line systems of logging, and in the accompanying drawings I have shown it in connection with a system of each type.

It is an object of my invention to provide a sky line logging system in which the tail end of the sky line may be easily and quickly shifted laterally. In so doing it is my intention generally to employ a cross cable from which the tail end is shiftable laterally of the trackway cable. It is my object, in connection with such systems, to so rig the sky line, its supports and guys, that practically all strain is removed from the cross cable in directions longitudinally of the trackway cable, that is, laterally of the position of the cross cable.

A further object is the provision of such a system in which the sky line may be quickly and easily shifted from one tail hold to another, and will automatically adjust itself to the new position along the cross cable.

A further object is the provision of such a system by means of which a tail hold may be shifted from one side to the other of a mast which supports the cross cable intermediate its ends with great facility.

A still further object is the provision of a sky line system which may be employed for logging in broken country and in places where it would ordinarily not be feasible to employ a sky line by reason of the position of the donkey engine beyond a hump or hill from the tail support, or because of the inability to secure a fixed tail mast at the place where such a mast is desired.

My invention comprises the novel elements of the logging system, the shifting means therefor, and so much of the system itself as is shown in the accompanying drawings, described in the specification, and particularly defined in the claims terminating the same.

In the accompanying drawings I have shown my system in operation under various conditions and illustrated also in connection with both a slack and a fixed sky line, all in forms now preferred by me.

Figure 1 is a plan view of a logging system employing my invention in conjunction with a slack trackway cable system.

Figure 2 is a detail of the tail hold of the same system, illustrating particularly a manner of shifting tail holds from one position to another.

Figure 3 is an elevation looking in the direction of the cross cable and illustrating the tail hold and the rigging for shifting the same.

Figure 4 is a perspective view showing my system employed in connection with a fixed sky line system in rough ground.

My invention is herein illustrated and described as particularly applied to the logging systems shown in Patent No. 1,151,299 to Shaw, and my own Patent No. 1,019,170. It will be understood, however, that this is merely for purposes of illustration and that the particular system employed for handling the logs is relatively unimportant, except as will be pointed out hereinafter, and defined in the claims.

My present invention consists of an improved means for providing a tail hold for sky line systems, or for other systems if desired, by means of which the tail hold may be shifted laterally so that in all cases the logs may be picked up from beneath the sky line without swinging the line or carrying the fall block any appreciable distance to one side or the other of the main sky line. This is of advantage in two ways, first in eliminating the work and trouble of swinging or carrying the fall block to one side of the main line, with consequent entanglement of the lines, and second, in enabling the work to be done at a greater rate of speed than by the employment of systems which necessitate a tedious and time-consuming shifting of the tail hold from one mast to another.

In Figures 1, 2 and 3, I have shown my invention in connection with what is known as the "MacFarlane" sky-line system, illustrated in my Patent No. 1,019,170, referred to above. In this system, briefly, a sky line or trackway cable 9 extends between a head mast 90 and a tail support. A log carriage 91 is hauled in along the sky line 9 by means of a haul-in line 92 connected thereto and

running over a block upon the head mast 90 to a drum of a donkey engine 93. A haul-back line 94, secured to the carriage 91, is suitably guided in blocks 95 and returns to a drum of the donkey engine 93. The sky-line 9 in this particular system is intended to be slackened off to lower the carriage 91.

Instead of the ordinary tail mast I substitute therefor a cross cable 1 which I shall term, in this instance, the tail cable. This is stretched between several masts 10, of which there may be and preferably are more than two, so that there is provided a mast to support the tail cable 1 intermediate as well as at its ends. The terminal masts 10 are, of course, suitably guyed to provide against strains longitudinally of the tail cable 1. These masts, however, may be five hundred feet or more apart and it would be impossible to guy them in such manner as to properly compensate for strain in the tail cable 1 laterally thereof.

A carriage 2 is movable along the tail cable 1 between any two of the masts 10. This carriage 2, which is shown in detail in Figure 3, is provided with means for supporting the tail end of the sky line 9. I have shown the carriage as provided with a shoe 22 depending therefrom and receiving a stub line 3 which, with an anchor line 4, forms in effect a continuation of the sky line 9. I desire, however, that the sky line terminate just short of the carriage 2 and that the stub line be suitably connected thereto, as by a releasable shackle 31. I also prefer that the stub line 3 be removably connected to the anchor line 4, as by a second shackle 32. The purpose for this will appear later.

The carriage 2, it will be noted, is supported by rollers 21 freely rotatable so that the carriage may travel along the tail cable 1 and may adjust itself freely therewith in accordance with the stresses placed upon it. The system is shown in Figure 1 with the anchor line 4, which is connected to an anchoring stump 41, the stub line 3, and the sky line 9, as forming a continuous straight line and in this manner determining the position of the carriage 2 lengthwise of the tail cable 1. Obviously if, instead of the stump 41 forming the anchor, a stump 43 were selected at one side of the stump 41, and sky line, the stub line and the anchor line would be shifted into a new straight line, as indicated by the dotted line in Figure 1, and the carriage 2 would then automatically move along the tail cable 1 to take up a new position in this straight line.

I have shown, in Figure 3, a shifting means which may be employed when it is desired to change the tail hold to a new position. This comprises a slack pulling line 5, one end of which is passed through a block 25

upon the carriage 2 and thence to a connection with the end of the sky line, as, for instance, at the shackle 31, and the other end of which is connected to the haul-in line or, for convenience, to the log carriage 91. Between its ends the slack pulling line 5 passes through a block 51 which is anchored at a convenient spot near the position of the carriage 2. By hauling in upon the haul-in line 92 the slack pulling line 5 is placed under tension and thereupon the stub line and anchoring line, which have been slackened, may be disconnected at the shackle 32. The sky line is then slackened off, and the slack pulling line 5 disconnected.

To the shackle 32 is now connected one end of a shifting line 6. The other end of this shifting line is connected to the haul-in line 92, or, like the slack pulling line 5, to the carriage 91. Between its ends the shifting line is passed through a block 62 which is placed at the new tail hold, as, for instance, the stump 43. These connections are best illustrated in Figures 2 and 3. By now hauling in on the shifting line 6 the end of the stub line 3 will be shifted laterally to its new position as indicated by the dotted lines in Figures 1 and 2, and the new anchor line 4', which had been previously prepared, may then be attached to the shackle 32 at the end of the stub line. The shifting line 6 may then be disconnected.

As the shifting line 6 was hauled tight, the carriage 2 was pulled along the cross cable 1 and automatically assumed a new position thereon in the straight line of the sky line. It will be noted that the actual tail hold, that is the anchor stump as 41 or 43, to which the end of the sky line is connected through the stub line 3 and the anchor line 4, is well beyond the cross cable 1 and ordinarily is below the level thereof. Through this combined stub line and anchor line all stresses in the direction of the sky line are resisted and all lateral stresses upon the tail cable 1 are removed. The tail cable 1 therefore has only the weight of the carriage 1, augmented at times through the vertically downward component of the stress along the sky line, to support.

When it is desired to shift the tail hold from one side to the other of an intermediate mast 10, it is necessary only to provide a duplicate carriage upon the opposite side of this mast, the duplicate carriage being rigged with a stub line 3 running through its shoe 22, and then to connect the shifting line 6 to the shackle 31 instead of the shackle 32. When the line is hauled in the sky line is brought up to a connection with the new stub line 3. In this manner shifting from one side to the other of an intermediate mast is practically as simple as in shifting from one tail hold to another along the cable 1.

In Figure 4 I have illustrated my invention in a slightly different form, as applied to the "North Bend" system, shown in the Shaw patent referred to heretofore. It will be seen from this view that it was desirable to provide a tail support for the fixed sky line 9 at a point which, by reason of a gully was at some considerable elevation above the surface of the earth at this point. The system, in the illustration, is also rigged with the donkey out of sight beyond a ridge on the near side of a small valley. In order to provide a proper tail hold at the proper point, a tail cable 1 is rigged between two masts 10 as in the former system, and the carriage 2 is movable therealong exactly in the manner described heretofore. In order to carry the logs over the hump on the near side of the valley, a second cross line 11 is rigged between two masts 12 at about the ridge of this hump. An open-side carriage 24 is movable along the cross cable 11 and the log carriage 91 is movable past the open face of the carriage 24. This form of carriage being relatively common, and as it forms no part of my invention, I have not deemed it necessary to illustrate it in more detail.

By shifting the position of the stub line 3 and its attached anchor line in this form, not only the carriage 2 is shifted but also the carriage 24, automatically, as the sky line 9 is tensioned in its new line. Such a ring enables an operator to pick up logs in quite rough territory and without the necessity of shifting the donkey for each hump or rise of ground.

What I claim as my invention is:

1. The combination with a trackway cable, of an elevated cross cable, for supporting the trackway cable, and means for relieving the cross cable of strains in the direction of the trackway cable.
2. A tail support for an elevated cableway comprising a transversely extending elevated cable and an anchor line connected with the cableway.
3. A tail support for an elevated cableway comprising a transversely extending elevated cable, an anchor line and a support for the cableway movable along said transverse line.
4. The combination with a trackway cable, of a transversely extending elevated tail cable, a carriage movable along said tail cable, and supporting the trackway cable, and a tail anchor line connecting said carriage with a fixed anchor beyond the tail cable.
5. The combination with a trackway cable, of an elevated transversely extending tail cable, a carriage supporting the tail end of the trackway cable, and movable along

the tail cable, and a line passing through said carriage, and connected at one end to a fixed anchor beyond the tail cable, and at its other end to the trackway cable.

6. In combination, a trackway cable, a transversely extending elevated tail cable, a carriage movable along the tail cable, a stub line passing through said carriage, and connected at one end to the tail end of the trackway cable, and an anchor line secured to the other end of said stub line, and secured at its other end to a fixed anchor beyond the tail cable.

7. In combination, a trackway cable, a transversely extending elevated tail cable, a carriage movable along the tail cable, a stub line passing through said carriage, and connected at one end to the tail end of the trackway cable, and an anchor line secured to the other end of said stub line, and secured at its other end to a fixed anchor beyond the tail cable, a slack-pulling line passing through said carriage, and connected at one end to the tail end of the trackway cable, a haul-in line paralleling said trackway cable, said slack-pulling line passing through a block and thence returning and secureable to said haul-in line.

8. In combination, a trackway cable, a transversely extending elevated tail cable, a carriage movable along the tail cable, said trackway cable terminating short of the carriage, a stub line supported from said carriage, and connected at one end to the tail end of the trackway cable, an anchor line connecting its other end to a fixed anchor beyond the tail line, means for slackening off the connection between said stub line and anchor line to permit their disengagement, and a shifting line secureable to the then free end of the stub line, and running through a block at a new anchor to a power source, to effect the shifting of the trackway cable to a new position.

9. Means for shifting the tail support of a cableway system which includes a transversely extending tail cable, a trackway cable having its tail end supported therefrom and movable therealong, and a haul-in line paralleling said trackway cable, which means comprises a shifting line connected at one end to said haul-in line, and a block beyond the tail line receiving said shifting line and anchored at a new position of the tail support, the other end of said shifting line being connected to the end of said trackway cable, and a slack-pulling line connected at one end to the tail end of the trackway cable, thence passing through said carriage, a fixed block through which the slack pulling line passes, being then fastened to the haul-in line.

10. An end support for a cableway comprising an elevated cable extending transversely of the line of the main cable, a support for the main cable carried by and mov-

able along said transverse cable and an anchor line adapted for connection with the main cable.

11. In combination, a trackway cable, a transversely elevated tail cable, another cross line intermediate the ends of the trackway cable, a carriage movable along each of said cross lines, and supporting the trackway cable therefrom, and means for anchoring the tail end of said trackway cable beyond said tail cable.

12. In combination, a trackway cable, laterally shiftable means for anchoring its tail end, a cross cable intermediate its ends, a carriage movable freely therealong and supporting the trackway cable, said carriage being automatically shiftable laterally as the tail support and anchor are shifted laterally.

13. The combination with an elevated cableway including a carriage and means for operating it upon said cableway, of an end support for the cableway comprising a transversely extending elevated cable, an anchor line connected with the main line, a support for the anchor line carried by and movable along the said transverse line, and means operable by the carriage to slacken the anchor connection whereby it may be re-

30 secured at a new location.

14. The combination with an elevated cableway including a carriage and means for operating it upon said cableway, of an end support for the cableway comprising a transversely extending elevated cable, an anchor line connected with the main line, a support for the anchor line carried by and movable along the said transverse line, and means for laterally shifting the anchorage comprising

40 a line secureable by one end to the end of the

cableway main line and by its other end to the carriage.

15. The method of laterally shifting a sky line support in a cable system including a sky line, an elevated cross line supporting the same, traveling lines paralleling the sky-line, and an anchor line extending beyond the skyline, which method comprises operating a slack-pulling line through said traveling lines to produce slack in the anchor line beyond said cross lines, disconnecting said anchor line and skyline, and in then operating a shifting line connecting the skyline with the new support, by means of a connection with the travelling lines.

16. The method of laterally shifting a skyline support about an intermediate mast in a cableway system comprising a skyline, a cross cable supporting an end of the skyline and supported from the masts, and carriages thereon between each pair of masts, a log carriage movable along the skyline, log carriage control lines, and an anchor line connected to the skyline inwardly of the cross cable carriage, which method comprises operating a slack-pulling line with said log carriage control lines, to produce slack in the anchor line to permit disconnecting the anchor line from the skyline inward from the cross cable carriage, operating a shifting line connecting the log carriage control lines and the end of the skyline with a carriage on the opposite side of an intermediate mast, and then connecting a new anchor line through the latter carriage to the end of the skyline.

Signed at Seattle, King County, Washington, this 23rd day of February, 1923.

CHARLES E. MacFARLANE.
